Primary Examiner — Ian Simmons*Assistant Examiner* — Samantha Q Lawrence(74) *Attorney, Agent, or Firm* — Merchant & Gould P.C.(57) **CLAIM**

The ornamental design for a prefabricated module design, as shown and described.

DESCRIPTION

FIG. 1 is a bottom view of a prefabricated module.

FIG. 2 is a front side view of the prefabricated module.

FIG. 3 is a back side view of the prefabricated module.

FIG. 4 is a short side view of the prefabricated module; and,

FIG. 5 is a perspective view of the prefabricated module.

The broken lines shown in FIGS. 2 and 3 illustrate portions of the prefabricated module that form no part of the claimed design.
